UNITED STATES PATENT OFFICE.

JOHN RAPHAEL ROGERS, OF BROOKLYN, NEW YORK, ASSIGNOR TO MERGENTHALER LINOTYPE COMPANY, A CORPORATION OF NEW YORK.

TYPOGRAPHICAL COMPOSING-MACHINE.

1,072,653.

Specification of Letters Patent.

Patented Sept. 9, 1913.

Application filed January 27, 1912. Serial No. 673,886.

To all whom it may concern:

Be it known that I, JOHN RAPHAEL ROGERS, a citizen of the United States, residing in Brooklyn, county of Kings, and 5 State of New York, have invented a new and useful Improvement in Typographical Composing-Machines, of which the following is a specification.

My invention relates to typographical 10 composing machines, such as linotype machines of the general organization represented in Letters Patent of the United States, No. 436,532, to O. Mergenthaler, wherein circulating matrices are released from a 15 magazine in the order in which their characters are to appear in print and then assembled in line, together with expanding spacers, the composed line transferred to the face of a mold, the mold filled with 20 molten metal to form a slug or linotype against the matrices which produce the type characters thereon, and the matrices thereafter elevated and returned through a distributing mechanism to the magazine or 25 magazines from which they started.

More particularly the invention relates to that class of typographical machines in which are employed type or matrices provided with two or more characters, and devices by which the position of the type or 30 matrices may be varied so that each will present one or another of its characters in the line, as demanded. Such an arrangement is disclosed in my Letters Patent, No. 615,909, 35 although the present construction differs therefrom in various particulars which will be subsequently set forth more specifically. For instance, when plural-character type or matrices have been assembled at different 40 levels, it is customary to restore them to the same level before distribution, and in the said Letters Patent this leveling operation is effected by the employment of a retractable ledge or support in the casting or first 45 elevator. In the form here illustrated and described, the supporting ledges in the first elevator are fixed and permanent, and therefore the leveling is effected at a subsequent point in the cycle of operations, which feature generically is also well known. Thus, 50 sometimes the leveling is effected in the upper transfer channel after the type or matrices pass from the first elevator and before they are moved into engagement with the 55 sustaining bar of the distributing or second

elevator. Again, and as disclosed in my application for Letters Patent Serial No. 559,784, filed May 5, 1910, the type or matrices are transferred to the second elevator at different levels and are permitted to move 60 to the same level therein.

In the present instance, I employ a second elevator which is formed not only to receive type or matrices at different levels, but also to sustain them in this condition during 65 their journey to the distributing mechanism; and in connection with such an elevator I provide means whereby the type or matrices are brought to a common level after they leave the elevator and before they are delivered to the distributing mechanism.

These and other improvements are illustrated in the accompanying drawing in preferred form by way of example and as applied to a linotype machine, but obviously 75 many changes and variations may be made therein and in their mode of application without departure from the scope of the invention; and generally speaking I desire it to be understood that I do not limit myself 80 to any specific form or embodiment except in so far as such limitations are specified in the claims.

Referring to the drawing:—Figure 1 is a longitudinal vertical section, partly 85 broken away, through the upper transfer channel, showing the first and second elevators in operative relation thereto; Fig. 2 is a transverse vertical section, taken substantially on the line 2—2 in Fig. 1; 90 Fig. 3 is a longitudinal vertical section through the distributor box and the second elevator in operative relation thereto, and Fig. 4 is an end view of the distributor box, etc., taken substantially on the line 4—4 in 95 Fig. 3.

The matrices X are provided with the projecting lugs or ears X¹, which lugs or ears are formed in the present instance with transverse notches or recesses X². Fig. 1 100 illustrates the position of the parts when the composed line of matrices X and spacers Y is being transferred from the first elevator A into the upper transfer channel B. As previously stated, the first elevator A is 105 formed with fixed rails or ledges A¹ and A², the lower ledges A¹ engaging beneath the ears X¹ of the matrices to sustain the latter in their lower position, and the upper ledges A² engaging in the notches or recesses X² 110

of the matrices to sustain them in their upper position. The line is transferred from the first elevator to the channel in the customary manner, the first effect of such transfer being the separation of the spacers Y therefrom by reason of the engagement of the spacer ears in the grooves B¹, along which the spacers are restored to their magazine Y¹ in the manner well understood in the art. Simultaneously the matrices X are moved into engagement with the second elevator C, which differs from the elevator disclosed in my before-mentioned application, in that it is not only provided with inwardly projecting ledges or flanges C¹ at the bottom thereof to engage under the ears X¹ of the lower matrices, but also with inwardly projecting ledges or flanges C² near the top thereof corresponding in location to the upper fixed ledges A² in the first elevator A. In the event that the first elevator A is not brought into immediate proximity to the second elevator C, the transfer channel B may be similarly provided with fixed ledges B², so located as to fill the gap between the ledges A² and C², and in such manner that the ledges A², B² and C² constitute a single continuous ledge to engage the notches X² as the matrices are moved from the first elevator to the second elevator. In this way, the upper matrices are delivered to the second elevator in the same relation, and when the elevator rises to convey the matrices to the distributing mechanism, they are still retained therein by the engagement of the ledges C² with the notches X² (see also Fig. 2). The notches X² are located at a proper point in the ears X¹ so as to make the distance between the ledges A¹ and A² in the first elevator correspond to that between the two characters in the matrix, as will be understood by those skilled in the art. It should also be noted that the channel B is formed with the customary ledge B³ to engage beneath and support the lower matrices as they pass from the first elevator.

In connection with this construction and arrangement, whereby the matrices are sustained at different levels in the elevator C, I have provided means whereby they are brought to a common level before they are presented to the distributing mechanism, and these means will now be described. Fig. 3 shows the elevator C in its uppermost position and in operative relation to the distributor box E, into which the matrices are transferred by the slide or pusher D, which is operated in the customary manner and in itself constitutes no part of the present invention. In the particular form illustrated, the distributor box E is formed at one end with the downwardly extending surface or bevel E² at its upper side, and with the upwardly extending surface or

bevel E¹ at its lower side. As the matrices are moved into the box from the elevator, those in the upper position are depressed by the surface E², and those in the lower position are elevated by the surface E¹, so as to bring them to a common level, as clearly shown in the drawing. The matrices are now forced through the box by the transfer slide, and at the opposite end thereof are delivered one by one to the vertically reciprocated lifter finger F, whereby they are transferred to the threads of the ordinary conveyer screws H, and by them in turn to the customary rail or bar G, along which they pass and from which they drop into their appropriate magazine channels, as set forth for instance in the Mergenthaler patent previously mentioned. The finger F receives its reciprocating motion from the arm F¹, which in turn is actuated by suitable connections from the arm H² and cam H¹ upon the end of one of the distributor screws H (see Fig. 4). These particular features are however well known in the art and in themselves constitute no part of the present invention.

As previously stated I have shown my invention in preferred form by way of example, and obviously there will be many changes and variations therein and in their mode of application, which will suggest themselves to those skilled in the art and still be comprised within its spirit.

Having thus described my invention, its construction and mode of operation, what I claim and desire to secure by Letters Patent of the United States is as follows:

1. In a typographical machine, the combination of distributing mechanism and the elevator to transport the type or matrices thereto, the said elevator being provided with means to receive and sustain them at different vertical levels.

2. In a typographical machine, the combination of distributing mechanism, means for presenting type or matrices thereto at different levels, and means for bringing the type or matrices to a common level before their distribution.

3. In a typographical machine, the combination of the distributing bar, an elevator for sustaining the type or matrices at different levels, and means for bringing the type or matrices to a common level in their passage from the elevator to the distributing bar.

4. In a typographical machine, the combination of the distributor box, an elevator for sustaining the type or matrices at different levels, and means for bringing the type or matrices to a common level in their passage from the elevator to the distributor box.

5. In a typographical machine, the combination of distributing mechanism and the

second elevator C to transport the type or matrices thereto, the said elevator being formed with the sustaining ledges C-1 and C-2 to sustain the type or matrices at different levels therein.

6. In a typographical machine, the combination of distributing mechanism, the elevator to transport the type or matrices thereto, the upper transfer channel through which they are transferred to the elevator, and means for presenting the type or matrices at different levels to said channel, the said channel and elevator being each provided with corresponding means to receive and sustain the type or matrices at such different levels.

7. In a typographical machine, the combination of distributing mechanism, the second elevator to transport the type or matrices thereto, the upper transfer channel through which they are transferred to the elevator, and the first elevator by which they are transported to said channel, both ele-

vators and the channel being provided with corresponding means to support the type or matrices at different levels during their transfer.

8. In a typographical machine, the combination of distributing mechanism, the second elevator to transport the type or matrices thereto and provided with means to receive and sustain them at different levels therein, the first elevator provided with means to sustain the type or matrices at corresponding levels therein, and means to transfer the type or matrices from the first elevator to the second elevator without change of level.

In testimony whereof I hereunto set my hand this twenty-third day of January, 1912, in the presence of two attesting witnesses.

JOHN RAPHAEL ROGERS.
